SPRINKLER

John S. Colombini, Detroit, Mich., assignor to Stamping Products & Mfg. Co., Detroit, Mich.,
a corporation of Michigan

Application June 6, 1950, Serial No. 10,377

Term of patent 7 years

(Cl. D91—1)

To all whom it may concern:

Be it known that John S. Colombini, a citizen of the United States of America, and a resident of Detroit, in the county of Wayne and State of Michigan, has invented a certain new, original, and ornamental design for A Sprinkler, of which the following is a specification, reference being had to the accompanying drawing, forming a part thereof, and wherein:

Fig. 1 is a perspective view, showing my new design for a sprinkler;

Fig. 2 is a perspective view of the sprinkler shown in Fig. 1 and showing the opposite side thereof; and

Fig. 3 is a top plan view of the sprinkler shown in Figs. 1 and 2.

The dominant features of my design are shown in solid lines.

I claim:
The ornamental design for a sprinkler, substantially as shown and described.

JOHN S. COLOMBINI.
